DEVICE FOR DISPENSING MATERIAL FROM
COLLAPSIBLE PASTE TUBES

Raymond D. Ruch, Burbank, Calif.

Application April 26, 1949, Serial No. 89,716

12 Claims. (Cl. 222—103)

1

This invention relates generally to the class of dispensing and is directed particularly to improvements in devices for dispensing material from collapsible paste tubes, more especially for the dispensing of tooth paste.

A principal object of the present invention is to provide a dispenser for ejecting the contents of a collapsible tube wherein means is employed for progressively applying pressure against opposite sides of the tube from the closed end, toward the discharge or nozzle end, without the usual procedure of either rolling the tube or squeezing it together by progressing rollers or sliding elements, use being made of a plurality of pairs of opposing and coacting compression fingers for squeezing and collapsing the tube.

Another object of the invention is to provide in a dispenser of the character stated, means for supporting a collapsible paste tube in a suitable housing between two rows of relatively shiftable press fingers, with means movable in the housing longitudinally of the tube and the rows of fingers for progressively moving together coacting fingers of the two rows to compress the tube body therebetween.

Another object of the invention is to provide a dispenser for ejecting the contents of a collapsible paste tube wherein a plurality of pairs of coacting compressing or squeezing fingers are employed between which the paste tube is mounted, said fingers carrying cam follower pins, with a camming member supported for movement longitudinally of the rows of fingers and having co-operating camming surfaces which progressively engage the finger pins to force the fingers together to squeeze the interposed tube.

Another object of the invention is to provide a device of the above described character wherein said camming means is provided with spaced parallel portions between which a pair of finger pins is held as the next succeeding pair of fingers is functioning to compress the tube whereby to prevent the rearward movement of the paste in the tube.

Still another object of the invention is to provide a device of the character stated wherein novel means is provided for mounting the paste tube in the device whereby there is provided a discharge nozzle which is coupled with the paste tube nozzle and which has a sliding cut-off.

Other objects and advantages of the invention will become apparent as the description of the same proceeds and the invention will be best understood from a consideration of the following detailed description taken in connection with the

2

accompanying drawings forming a part of the specification, with the understanding, however, that the invention is not to be limited to the exact details of construction shown and described since obvious modifications will occur to a person skilled in the art.

In the drawings:

Figure 1 is a view in top plan of a dispensing device for paste tubes, constructed in accordance with the present invention.

Figure 2 is a view in front elevation of the device, with a portion of the front wall being broken away.

Figure 3 is a view in side elevation of the device with a portion of the front and side walls broken away.

Figure 4 is a longitudinal section taken substantially on the line 4—4 of Figure 2.

Figure 5 is a transverse section taken substantially on the line 5—5 of Figure 2.

Figure 6 is a transverse section taken substantially on the line 6—6 of Figure 2.

Figure 7 is a sectional view taken substantially on the line 7—7 of Figure 2.

Figure 8 is a sectional view taken substantially on the line 8—8 of Figure 5 with the fingers separated;

Figure 9 is a sectional view taken substantially on the line 9—9 of Figure 5;

Figure 10 is an enlarged fragmentary detail view of the latch as herein embodied;

Figure 11 is an enlarged fragmentary detail view at one end portion of a cam block and associated arm; and

Figure 12 is an elevational view of a tail piece as herein comprised and unapplied.

Referring now more particularly to the drawings the numeral 10 generally designates a relatively long housing or casing in which are mounted the paste tube and the operating parts 40 by which the tube is squeezed or compressed to effect the ejection of the contents downwardly through the hereinafter described discharge nozzle.

The housing 10 comprises the back wall 11, side walls 12 and the forwardly converging front wall panels 13 which merge with the central front panel 14. The latter panel has therein a door opening 15 which extends through the bottom 50 end of the panel and throughout the major portion of the length thereof as shown most clearly in Figure 2.

The top of the housing is closed by the top wall or top plate 16 which, while it may be secured in position in any suitable manner, is here

shown as being held down by screws 17 which are threaded into suitable lugs 18 formed on the inner surfaces of the adjacent walls as shown in Figure 1.

At the lower end of the housing is the bottom wall 19 which is elevated in the forward part thereof to join the lower ends of the front wall panels 13 and 14, which panels are of slightly less length than the side walls and the back wall as shown in Figure 3. Formed rearwardly in the elevated forward portion of the bottom wall, which portion is designated 19', is the recess 20 which is of the same width as the door opening 15 with which it merges. At the two sides of this recess 20 there are formed integral with the elevated front portion 19' of the bottom wall, the depending ears 21 which are provided with the aligned screw threaded openings 22 for the purpose hereinafter described.

Formed to position in the bottom wall opening or recess 20 is a relatively thick block of material which is generally designated 23 and which constitutes a foot upon which the paste tube is supported in the manner hereinafter described. This body 23 substantially fills the opening 20 as shown in Figure 7 and at its front side, it is formed integral with the lower end of a door 24 which closes the door opening 15. This door 24 carries a suitable latch 25 at its upper end for securing the door in closed position.

The body 23 has formed therein from the top, a tapped bore 26 of a suitable diameter to receive the threaded nozzle 27 of a paste tube 28. The depth of the tapped bore 26 is slightly greater than the length of the paste tube nozzle 27 as shown and from its bottom it continues down through the body 23 to open through the lower end thereof, providing the paste discharge passage 29.

The body 23 is maintained in position between the ears 21 for swinging movement, by the pivot screws 30 which are threaded into the openings 22 and have smooth inner end portions 31 which form pivot trunnions which engage in suitable openings in the adjacent sides of the body 23. Thus it will be seen that the door and the body can be oscillated on these pivots 31 when the latch 25 is released, to facilitate the insertion of the paste tube.

As shown in Figure 4 the body 23 which forms, as previously stated, a base or foot portion for the door, has a recess 32 formed in the back part thereof and in this recess is positioned the tail piece 33 for a shut-off cap 34 which fits against the curved underside of the body 23. Extending transversely across the cut out space 22 and through the tail piece 33 of the cap is a pivot pin 35 which has its ends secured in the body 23 at opposite sides of the cut out 32.

The upper end of the tail piece 33 has a flat top surface 36 while the rear edge of the tail piece slightly below the top surface has formed therein a notch 37.

As shown in Figure 4 a second bore, designated 38 is formed in the body 23 from the top thereof and just behind the bore 26. In this bore is slidably positioned a latch finger 39 which rests upon the flat top portion 36 of the latch tail piece 33 and which is pressed downwardly by a spring 40 which is retained in position by a screw 41 threaded in the upper part of the bore 38. This spring through the medium of the latch finger 39 holds the cap 34 against free movement and when the cap 34 is swung rearwardly to uncover the discharge end of the passage 29, the finger engages in the notch 37 and thus holds the cap open

while paste is being ejected from the passage 29.

At the bottom of the housing each of the side walls 12 carries two inwardly projecting guide lugs or flanges 42 which are spaced apart in a front to rear direction in the housing as shown in Figure 7. In the upper part of the housing directly above the guide lugs or flanges 42, each side wall carries a corresponding upper pair of guide flanges or lugs 43.

- 10 At each side of the housing there is disposed vertically a flat bar 44 which is engaged at its lower end between a pair of guide lugs 42 and at its upper end between a pair of guide lugs 43. Each of these bars carries an inwardly extending foot flange 45 at its bottom end and an inwardly projecting ear 46, the flat sides of which are in a vertical plane extending transversely of the housing and accordingly perpendicular to the foot flange 45 which is horizontally disposed and rests upon the bottom wall or floor 19 to which it is secured by a screw 47 as shown in Figures 2 and 3.

- 20 At the rear sides of the ears 46 each of the bars has a longitudinal groove in its inner face 25 as indicated at 48 and these grooves, which are in opposed relation, receive the longitudinal edges of a vertically disposed finger carrying or retainer plate 49. This plate is fixed to the vertical side bars between which it is positioned, by screws 30 passing through the ears 46 and into the plate at the bottom of the latter as shown in Figures 2, 3 and 4.

- 25 In addition to the inwardly projecting ears 46 at the lower ends of the bars 44, such bars carry 35 corresponding ears 46' at their upper ends, to which the plate 49 is secured by screws 50' as shown in Figures 2 and 3.

- 30 The plate 49 is provided with a plurality of 40 horizontally spaced pairs of guide slots 51 each of which opens at its outer end through a vertical longitudinal edge of the plate 49 while the inner ends of the guide slots are in relatively closely spaced relation at opposite sides of the longitudinal center of the plate 49 as is clearly shown in Figure 2. Thus at each side of the longitudinal center of the plate 49 is a vertical series of horizontal slots, each slot upon one side being horizontally spaced from and in the same plane with a slot on the other side to form a pair. As 45 will be readily apparent the open outer ends of these slots 51 are closed by the bars 44 against which the longitudinal edges of the plate 49 bear.

- 50 In each of the slots 51 is slidably mounted 55 a finger block 52. Each of these blocks is of slightly greater length and width and the length extends lengthwise of the slot 51 and the top and bottom edges of the block have therein guide slots 53 which receive the upper and lower edges of the plate slots. Formed integral with the front side of each finger block 52, is the relatively long 55 finger 54 which extends forwardly to close proximity with the rear side of the front wall 14. These fingers 54 have opposing flat faces which, as shown in Figure 5, come into relatively close 60 opposed relation when the blocks of each horizontally spaced pair of fingers are moved together. Consequently when the fingers are moved together in the manner shown in Figure 5 the interposed paste tube body 28 will be subjected to squeezing pressure.

- 65 Each of the finger blocks 52 has secured therein and extending transversely therethrough, a pin 55 which upon the rear or back end carries a roller 56 which functions as a cam follower.

- 70 Connected with the forward end of each pin 55

is one end of a contractile spring 57 which extends laterally and has its other end secured to the adjacent bar 44 as indicated at 57'.

Disposed vertically in the rear part of the housing behind the central part of the plate 49 is a screw shaft 58. The lower end of the shaft has a journal 59' which is mounted in a bearing opening 59 in the bottom wall 19 and the upper end is likewise formed to provide the journal 60 which is rotatably mounted in the bearing opening 61 in the removable top wall 16.

At its upper end the screw shaft 58 carries a small spur gear 62.

Rotatably mounted in the bearing 63 formed through the central part of the top wall 16 is a short shaft 64 upon the lower end of which is carried, within the housing, the spur gear 65 which meshes with the gear 62 as shown in Figure 4.

Upon the upper end of the shaft 64 is mounted, outside the housing, the relatively large knob 66 by means of which the gear 65 may be manually turned to rotate the screw shaft 58.

The shaft 58 passes through and is threadably connected with a runner 67 which forms a part of a finger actuator which is moved vertically in the housing by the screw shaft 58 and which is generally designated 68.

The runner 67 has the two oppositely directed arms 69 which are horizontally disposed and are directed toward the side walls of the housing as shown in Figure 5.

Slidably mounted upon each of the arms 69 is a cam block 70 which is provided with a bore 71 in which the arm 69 engages. The outer end of this bore is suitably enlarged as shown in Figure 5 to receive a spring 72 and secured in the outer end of each arm 69 is a screw having a large head 73 which extends beyond the side of the arm 69 to overlie the adjacent end of the spring 72 and thus yieldingly maintain the cam block in position on the arm.

Each of the cam blocks 70 is formed upon the forward side to provide the inwardly converging camming faces 74 and the central camming face 75 which is disposed between and separates the convergent inner ends of the faces 74 and which parallels the line of movement of the cam block. These central vertical faces 75 of the two cam blocks are in spaced opposed relation and upon opposite sides of the central vertical plane passing from front to rear through the screw shaft 58 and between the working faces of the fingers 54. The space between the cam faces 75 is such as to permit the cam follower rollers 56 of a pair of fingers to pass therebetween when the finger blocks are fully moved together as illustrated in Figure 5 or, in other words, moved to full compression position. The finger blocks are shifted to this position by the downward movement of the cams which causes the lower sloping faces 74 of the two cam blocks to ride down against the rollers and gradually force them together to the maximum extent whereupon they enter between the opposing vertical cam faces 75 as shown in dotted outline in Figure 2.

In the operation of the present dispenser device, the door 24 is released and swung outwardly and downwardly so as to permit the placing of the tube 28 in position by screwing the nozzle 27 into the socket 26 in the foot piece or body 23 at the lower end of the door. If the runner or follower body 67 is at the lower end of the screw shaft 58 the shaft is suitably rotated to return the follower or runner to the top end of the shaft

and when it is in this position all of the pairs of fingers will be separated as shown in Figure 6 so that when the door 24 is closed the tube will be located vertically between the pairs of fingers.

5. It will be obvious, of course, that the flattened or compressed end of the tube must be disposed substantially parallel with the fingers 54 for the most efficient operation of the device.

After the tube has been placed in position in 10. the manner stated the ejection of the contents through the discharge passage 29 is effected by rotating the knob 66 to turn the shaft 58 in the proper direction to feed the runner or follower downwardly together with the cam blocks carried thereby. This operation will bring the lower inclined camming faces 74 against the top pair of rollers 56 and gradually force the rollers, together with the blocks 52 and the fingers 54 thereof, together, so as to apply squeezing pressure to the

15. tube. The applied pressure is in a straight line transversely of the tube and without sliding movement against the wall of the tube and consequently all danger of rupturing the tube or tearing it because of friction is avoided. As the 20. compressor unit 68 is moved downwardly the top pair of fingers will finally reach the limit of their inward movement whereupon the rollers 56 thereof will run onto the vertical opposed cam faces 75 and during this phase of the operation of the 25. device the next lower pair of rollers will be engaged with the inclined under faces 74 to gradually increase the squeezing action of the next 30. lower pair of fingers. By reason of the fact that the rollers 56 of the preceding fingers are between 35. the vertical camming faces 75 during the squeezing action of the next lower pair of fingers it will be seen that the movement of the contents of the tube can progress only downwardly. When the 40. next or second pair of fingers passes into the fully compressed position where their rollers 56 are engaging the vertical faces 75, the third lower pair of rollers will be moving up the inclined lower faces 74 and the top pair of rollers will be 45. moving onto the upwardly and outwardly inclined top faces 74 so as to permit the springs 57 to pull the top pair of fingers outwardly to separated relation. Thus it will be seen that as the 50. compressor unit moves downwardly the fingers will be successively pressed together against the wall of the tube to fully compress it while the preceding pair of fingers holds the tube compressed and this action continues until the bottom end of the tube is reached and the contents 55. completely ejected.

55. While there has been shown a manual means for turning the shaft 58 it will be obvious that any suitable mechanical means may be coupled with the shaft such as a small electric motor, if desired.

60. It will also be obvious that the device may be mounted in any suitable manner there being here illustrated apertured mounting ears 84 formed integral with the longitudinal edges of the back wall of the housing.

65. I claim:

1. A dispenser for paste tubes comprising a plurality of horizontally spaced pairs of sliding, opposed pressing fingers arranged in a longitudinal series, means for supporting a paste tube between the pairs of fingers, a runner supported for movement along a path extending lengthwise of the series of fingers, means for moving the runner along said path, and coacting means between the runner and the fingers for progress-

sively moving the pairs of fingers together to apply squeezing pressure to the interposed tube.

2. A dispenser for paste tubes comprising a plurality of horizontally spaced pairs of pressing fingers arranged in a longitudinal series, means for supporting a paste tube between the pairs of fingers, a runner supported for movement along a path extending lengthwise of the series of fingers, means for moving the runner along said path, coacting means between the runner and the fingers for progressively moving the pairs of fingers together to apply squeezing pressure to the interposed tube, and a body disposed at the end of the series of pairs of fingers having a threaded socket in which may be threadably engaged the discharge nozzle of a tube and a passage leading from the socket for the discharge of the contents of the tube, said body being shiftable relative to the pairs of fingers to move the tube into and out of position between the pairs of fingers.

3. A dispenser for paste tubes comprising a plurality of horizontally spaced pairs of pressing fingers arranged in a longitudinal series, means for supporting the paste tube between the pairs of fingers, a runner supported for movement along a path extending lengthwise of the series of fingers, means for moving the runner along said path, and coacting means between the runner and the fingers for progressively moving the pairs of fingers together to apply squeezing pressure to the interposed tube, the said coacting means comprising a pair of camming elements carried by the runner and cam follower members carried by the pairs of fingers for engagement by the camming elements as the runner progresses along said path.

4. A dispenser for paste tubes comprising a plurality of horizontally spaced pairs of pressing fingers arranged in a longitudinal series, means for holding a paste tube by the discharge nozzle thereof and maintaining the tube in position between the pairs of fingers, a runner supported for movement along a path extending lengthwise of the series of fingers, means for moving the runner along said path, means carried by the runner providing a pair of upwardly and inwardly converging camming faces, and a cam follower carried by the finger of each pair and arranged in a position to be engaged by the converging camming faces as the runner moves in one direction along said path to successively effect the forcible movement of the pairs of fingers together.

5. A dispenser of the character stated in claim 4, with spring means connected with said fingers and placed under tension upon movement of the pairs of fingers together to effect the retraction of the fingers upon disengagement of the followers from the cam faces.

6. A dispenser of the character stated in claim 4, wherein said camming faces merge at the convergent ends thereof with spaced parallel faces between which the cam followers of each pair of fingers moves and is held for a predetermined period in the advancing movement of the runner.

7. A dispenser for paste tubes comprising a relatively long housing body designed to be vertically disposed in the use of the dispenser, a plate member disposed vertically in the housing and transversely thereof, said plate member having upon each side of its longitudinal center a series of horizontal slots, each slot of one series being horizontally aligned with a slot of the adjacent series to form a spaced pair of slots, a body slidably mounted in each slot for inward and outward movement, a finger carried by each body, the bodies in each pair of slots forming a co-operating pair, each pair of bodies and the fingers carried thereby being adapted to be moved into relatively closely spaced relation at the center of the plate, means for supporting a paste tube in the housing in vertical position between the fingers carried by the pairs of sliding bodies, means by which the contents of the tube may be discharged downwardly from the tube when the tube is compressed, said bodies when moved together in pairs effecting the compression of the tube by the cooperating fingers carried thereby, a runner member disposed rearwardly of the plate for movement longitudinally thereof, means for moving the runner member, and cooperating means between the runner and the pairs of bodies for effecting the progressive movement together of the pairs of bodies as the runner is moved in one direction longitudinally of the plate.

8. A dispenser of the character stated in claim 7, wherein the said cooperating means comprises coacting camming bodies carried by the runner and cam follower elements carried by the sliding bodies, the elements of each pair of sliding bodies being engaged by the coacting camming elements in progressive movement of the runner to force the pairs of bodies and the fingers carried thereby toward the longitudinal center of the plate.

9. A dispenser of the character stated in claim 7, wherein the said cooperating means comprises coacting camming bodies carried by the runner and cam follower elements carried by the sliding bodies, the elements of each pair of sliding bodies being engaged by the coacting camming elements in progressive movement of the runner to force the pairs of bodies and the fingers carried thereby toward the longitudinal center of the plate.

10. A dispenser for paste tubes, comprising a relatively long housing which is vertically disposed in the use of the dispenser, a plate member disposed vertically within the housing and transversely thereof between opposite side walls, said plate member having upon each side of its longitudinal center a longitudinally spaced series of horizontal slots, the slots of one series being in spaced aligned relation with the slots of the other series to form horizontally spaced pairs of slots, a finger block slidably mounted in each slot for inward and outward movement, a finger carried by each block, the blocks and fingers of each pair of slots forming a cooperating pair of tube squeezing elements, a threaded screw shaft disposed vertically in the housing behind the longitudinal center of the plate, a runner threaded on said shaft for longitudinal movement in the housing, said runner having a pair of oppositely directed arms, a cam block supported upon each of said arms, said cam blocks having upwardly and inwardly convergent cam faces each merging with a vertical cam face, the vertical cam faces being in spaced relation, a cam follower roller carried by each finger block and positioned for engagement with an inclined cam face of a cam block, the inclined and vertical cam faces being arranged to simultaneously engage a pair of rollers to move the latter inwardly and maintain them in the inward moved position for a predetermined period during the advance movement of the runner, means yieldingly holding the cam blocks against outward movement on the arms, and

spring means normally urging separatory movement of the pairs of finger blocks.

11. A dispenser of the character stated in claim 10, with a door member in the forward part of the housing, a body forming a lower end portion of the door member, the body being pivotally supported to facilitate the swinging movement of the door member, said body being disposed in relatively close proximity to the front side of the slotted plate and having a downwardly extending paste discharge passage there-through, means for coupling the discharge nozzle of a paste tube with the door body for discharge into said passage and to maintain the tube in parallel relation with the inner side of the door and between the pairs of fingers when the door is in closed position.

12. A dispenser of the character stated in claim 10, with a door member in the forward part of the housing, a body forming a lower end portion of the door member, the body being pivotally supported to facilitate the swinging

movement of the door member, said body being disposed in relatively close proximity to the front side of the slotted plate and having a downwardly extending paste discharge passage there-through, means for coupling the discharge nozzle of the paste tube with the door body for discharge into said passage and to maintain the tube in parallel relation with the inner side of the door and between the pairs of fingers when the door is in closed position, and means carried by the door carried body forming a shut-off cap for the outlet end of said passage.

RAYMOND D. RUCH.
